LUGGAGE HANDLE

Benjamin M. Hamlin, Chicago, Ill.

Application August 29, 1938, Serial No. 227,293

3 Claims. (CL. 190—57)

This invention relates generally to new and useful improvements in handles, and more particularly, to a luggage handle of the type comprising a grip member covered with leather or other suitable material.

It is the main object of this invention to provide a handle of the character described which may be constructed from a few simple parts, easily assembled, and when so constructed and assembled, will present a handle which will not only be durable, but also of highly attractive and ornamental appearance.

Another object of the invention is to provide a luggage handle of the character described, comprising a pair of bracket members of suitable material, such as metal or the like, having sockets provided therein for the reception of the ends of the grip member, which grip member may be formed of wood or the like, and is adapted to be covered by a suitable material, which will be the same as that with which the luggage to which the handle is to be attached is covered, and novel and improved means for securely fastening the covering material to the grip member.

A still further object of the invention is to provide a luggage handle of the character described, comprising a grip member of wood or the like, having its end portions secured in metal brackets provided with sockets, and means provided in said sockets for securely fastening the ends of said grip member therein, and for also preventing rotary movement of said grip member when once secured in place.

A still further object of this invention is to provide a luggage handle of the character described, comprising a grip member of wood or the like, to the outer surface of which is adapted to be secured a suitable covering material, said grip member being provided with a longitudinal slot extending along its full length for receiving the ends of the covering material, and a rod adapted for disposition within said slot to retain the said covering material in place on the grip member.

With the foregoing and other objects in view which will appear as the description proceeds, the invention consists in certain novel features of construction, arrangement and combination of parts hereinafter fully described, illustrated in the accompanying drawing, and particularly pointed out in the appended claims, it being understood that various changes in the form, proportion, size and minor details of the structure may be made without departing from the

spirit or sacrificing any of the advantages of the invention.

For the purpose of facilitating an understanding of my invention, I have illustrated in the accompanying drawing, a preferred embodiment thereof, from an inspection of which, when considered in connection with the following description, my invention, its mode of construction, assembly and operation, and many of its advantages should be readily understood and appreciated.

Referring to the drawing in which the same characters of reference are employed to indicate corresponding or similar parts throughout the several figures of the drawing:

Fig. 1 is a view in perspective of a luggage handle constructed in accordance with the principles of my invention;

Fig. 2 is a longitudinal sectional view through the same;

Fig. 3 is a sectional view taken substantially on line 3—3 of Fig. 2;

Fig. 4 is a transverse sectional view taken substantially on line 4—4 of Fig. 2;

Fig. 5 is a sectional view through one of the 25 sockets within which the end of the grip member is received.

Referring to the drawing more specifically by characters of reference, the letter A designates a piece of luggage of any conventional construction, to which is secured my improved handle generally designated by the reference character 10.

In the embodiment illustrated, the handle comprises the grip member 11, which is formed of 35 any suitable material such as wood or the like, said member being shaped substantially as shown in the drawing, being of enlarged diameter at its central portion, gradually tapering towards the ends to provide the substantially cylindrical end 40 portions 12 and 13 which are adapted for disposition within the sockets 14 and 15, respectively, in suitable brackets 16 formed of metal. Said brackets 16 are provided with the opening 17 adjacent their lower ends, through which are 45 adapted to be passed the straps or staples 18, by means of which the handle 10 is permanently secured to the piece of luggage A.

The members 16 are of identical construction, and, as already stated, each includes adjacent 50 its upper end the socket for receiving the cylindrical end of the hand grip 11. The socket is of substantially circular formation, and has provided centrally thereof, the screw member 19, which is rigidly and permanently fixed in a disc 55

member 20 disposed therein, and is adapted for engagement within the end of the hand grip, as shown more clearly in Fig. 2. The socket has formed on its inner walls, spaced circumferentially, a plurality of rib portions 21, which ribs are adapted to bite into the side walls of the cylindrical end portions of the grip member 11, to thereby securely lock said grip member against turning within the brackets 16.

10 In the preferred embodiment of my invention, the ends 12 and 13 of the grip member are fixed within the sockets 14 and 15 by jamming the socket members 16 upon the assembled handle 10, causing the screw member 19 to be forced 15 into the ends of the grip member 11, the grip member having holes started in the ends for receiving the pointed ends of the screws 19. This jamming causes the threads of the screw member 19, besides gripping the member 11, to spread the 20 ends 12 and 13 within the sockets, causing the same to expand and further secure said handle ends 12 and 13 within said sockets 14 and 15, and upon said ribs 21.

It is well-known that the luggage highly popular at the present time is covered with a suitable fabric, and in order to enhance the appearance of this luggage, it is the purpose of this invention to cover the handle with the same material that the luggage is covered with, and in the present 30 case this is accomplished by surrounding or encasing the hand grip 11 with the suitable covering 22. In order to securely fasten the covering material 22 to the member 11, I provide adjacent the lower edge of said member a longitudinal 35 groove 23, which groove extends along the entire length of said member 11, and is adapted for receiving therein the free ends of the covering material 22, as shown more clearly in Fig. 4 of the drawing. In order to prevent said free ends 40 from becoming disassociated from the groove, I mount within the groove a suitable rod 24, said rod being substantially the same length as the hand grip 11, and the ends of said rod being disposed within the sockets 14 and 15 when the handle is in fully assembled position. Thus, it 45 will be noted, that it will be impossible for the covering material 22 to become disassociated from the hand grip 11 when the same had once been assembled.

50 From the above, it will be noted that I have provided a luggage handle which is constructed from only a few simple parts, which may be easily assembled, and when so assembled, will be durable and highly efficient for carrying out the 55 purposes for which it is designed.

It is believed that my invention, its mode of construction and assembly, and many of its advantages should be readily understood from the foregoing without further description, and it

should also be manifest that while a preferred embodiment of the invention has been shown and described for illustrative purposes, the structural details are nevertheless capable of wide variation within the purview of my invention as defined in 5 the appended claims.

I claim:

1. A luggage handle, comprising a hand grip provided with a longitudinal groove extending along its full length, a covering for said hand grip with the free edges thereof turned into said groove, a strip of metal forced into said groove for holding the edges of said covering in place, a pair of brackets having sockets adjacent their upper ends for receiving the free ends of said hand grip, means carried by said sockets for engagement with the ends of said hand grip, the free ends of said metal strip extending into said sockets for preventing displacement of said strip from said groove. 20

2. A luggage handle, comprising a hand grip provided with a longitudinal groove extending along its full length, a covering for said hand grip with the free edges thereof turned into said groove, a strip of metal forged into said groove for holding the edges of said covering in place, a pair of brackets having sockets adjacent their upper ends for receiving the free ends of said hand grip, means carried by said sockets for engagement with the ends of said hand grip, said last-mentioned means including a screw member 25 adapted for engagement within the end of said hand grip, and a plurality of circumferentially spaced rib portions provided on the inner surface of said socket for biting into the outer surface of said hand grip to prevent rotary movement thereof relative to the brackets when the hand grip is in assembled relation with said brackets. 30

3. A luggage handle, comprising a pair of metal brackets, each having a socket adjacent its upper end, a centrally located screw member disposed in each of said sockets and a plurality of circumferentially spaced rib portions provided on the inner surface of said socket, a hand grip adapted for assembly with said metal brackets, with the free ends of said hand grip arranged within said sockets, a covering for said hand grip, said hand grip being provided with a longitudinal groove extending along the full length thereof, the free edges of said covering being received within said groove, and a metal strip disposed in said groove and over the free edges of said covering for holding the latter in said groove, said metal strip having its free ends disposed within the sockets when the hand grip is in assembled relation with the brackets. 40 45 50 55
